Robert Y. Allen and Melvin Shaw, Los Angeles, Calif.,
assignors to Hoover Products, Inc., Youngstown, Ohio,
a corporation of Ohio

Filed May 16, 1960, Ser. No. 60,601

Term of patent 14 years

Figure 1 is a front perspective view of a toy animal figure showing our new design; and Figure 2 is a back perspective view thereof.

We claim:

The ornamental design for a toy animal figure, as shown.
